UNITED STATES PATENT OFFICE.

RICHARD LEE DEZENDORF, OF RICHMOND HILL, NEW YORK.

GAS-METER.

1,285,953.

Specification of Letters Patent.

Patented Nov. 26, 1918.

Application filed January 4, 1917. Serial No. 140,518.

To all whom it may concern:

Be it known that I, RICHARD LEE DEZENDORF, a citizen of the United States, residing at 432 Guion ave., Richmond Hill, county 5 of Queens, and State of New York, have invented certain new and useful Improvements in Gas-Meters, of which the following is a full, clear, and exact description.

My invention relates to improvements in 10 gas meters and has for its object to provide a novel, simple and efficient means for adjustably mounting the tangent post upon the tangent, so that its angular relation to the crank shaft may be varied as well as its 15 radial position, in order to adjust its position for correct operation.

The following is a description of an embodiment of my invention, reference being had to the accompanying drawings, in 20 which:

Figure 1 shows a plan view of a meter embodying my invention, the meter top being removed;

Fig. 2 shows a side elevation of the meter 25 tangent and the adjustable post thereon;

Fig. 3 shows in perspective the tangent together with the means for adjusting the tangent post, and

Fig. 4 shows a detail end view of the tangent and the movable member carrying the tangent post, together with the adjusting screws co-acting therewith, one of the adjusting nuts being removed.

Referring more particularly to the drawings, 1 is a meter case with the top removed, having the inlet 2 and the outlet 3; 25 4 is a registering train actuated by the shaft 5, driven by the gear 6, which in turn is driven by the worm 7 carried by the upper 30 end of the ordinary crank shaft; 8 is the tangent carrying the tangent post 9, to which are connected the lower flag arms 10 and 11, which in turn are connected to the upper flag arms 12 and 13, carried by the 35 flag wires 14 and 15 respectively.

In order to adjust a tangent post relatively to the crank shaft, it is necessary at times to move the tangent post through a small angle about the crank shaft. This has generally been done by unsoldering the tangent and re-soldering it in a new position. It also has been done by mounting the tangent post upon a movable member having an axis of rotation concentric with the axis of the 50 crank shaft. I have found that good re-

sults can be produced in a simpler manner and in carrying out my present invention provide a yoke 16 upon which the tangent post 9 is rigidly mounted. This yoke has an elongated opening surrounding the body 60 of the tangent so as to be laterally movable thereon. In the ends of this yoke are adjusting screws 17, whose inner ends engage the body of the tangent, as shown in Fig. 4. On the two sides of the adjustable yoke are 65 nuts 18 and 19 engaging screw threads upon the body of the tangent and serving as means for adjusting the yoke 16 upon the tangent at the desired radial distance from the axis of the crank shaft. The upper and lower 70 sides of the tangent are provided with horizontal surfaces which engage plain surfaces of the opening in the yoke so as to guide the yoke and maintain the tangent post in a vertical position.

In using my improved adjustable tangent post, I first loosen the screws 17 and by means of the nuts 18 and 19 move the yoke and tangent post lengthwise upon the tangent so that the distance between the axis 80 of the crank shaft and the axis of the tangent post is substantially the correct radial distance; I then move the yoke 16 to one side or the other by means of the adjusting screw 17 in which the proper angular relation between the tangent post and the crank shaft is obtained, and I then clamp the yoke permanently in that position by means of the screws 17 and nuts 18 and 19. By this means the angular position of the tangent 85 post can be adjusted without moving the tangent relatively to the crank shaft to which it is soldered. The adjustable yoke and post can be applied to old meters having the ordinary tangent, soldered to the crank 90 shaft in the ordinary manner.

As will be evident to those skilled in the art, my invention permits of various modifications, without departing from the spirit thereof or the scope of the appended claims. 100

What I claim is:

1. In a gas meter, the combination of a straight tangent, a yoke carrying a tangent post rigidly mounted thereon and having a horizontally elongated opening therein, said 105 opening surrounding said tangent and having its major axis horizontal and substantially at right angles to said tangent, and clamping nuts surrounding said tangent and engaging the sides of said yoke, the axis of 110

said nuts being in line with the axis of said tangent.

2. In a gas meter, the combination of a straight tangent, a yoke having a horizontally elongated opening therein having its major axis substantially at right angles to said tangent, and clamping nuts on said tangent engaging the sides of said yoke, and adjusting screws entering the ends of said 10 yoke for moving the same laterally relatively to said tangent.

3. In a gas meter, the combination of a straight tangent, a yoke having a horizontally elongated opening therein having its major axis substantially at right angles to 15 said tangent, and clamping nuts on said tangent engaging the sides of said yoke, said tangent having a horizontally extending guiding surface engaging the inner horizontal surface of said opening.

RICHARD LEE DEZENDORF.
